(57) **CLAIM**

The ornamental design for a surface configuration of a side of a vehicle, as shown and described.

DESCRIPTION

This application is related to the following co-pending applications, of the inventor, filed on even date herewith: application Ser. No. 29/151,801, entitled "Surface Configuration of a Vehicle and Toy"; application Ser. No. 29/151,818, entitled "Surface Configuration of a Door for a Vehicle"; application Ser. No. 29/151,817, entitled "Surface Configuration of a Door for a Vehicle"; application Ser. No. 29/151,797, entitled "Surface Configuration of a Front Fender for a Vehicle"; and application Ser. No. 29/151,816, entitled "Surface Configuration of a Rear Fender for a Vehicle".

FIG. 1 is a front view of a first embodiment of a surface configuration of a side of a vehicle according to my novel design;

FIG. 2 is a perspective view of the first embodiment of the surface configuration of a side of a vehicle according to my novel design;

FIG. 3 is a front view of a second embodiment of the surface configuration of a side of a vehicle according to my novel design; and,

FIG. 4 is a perspective view of the second embodiment of the surface configuration of a side of a vehicle according to my novel design.

The broken lines included in the drawings depict environment and are not part of the claimed design.
